UNITED STATES PATENT OFFICE.

RICHMON E. FRENCH, OF MEDINA, OHIO.

DESIGN FOR A BOTTLE OR SIMILAR ARTICLE.

SPECIFICATION forming part of Design No. 32,947, dated July 17, 1900.

Application filed June 9, 1900. Serial No. 19,778. Term of patent 14 years.

To all whom it may concern:

Be it known that I, RICHMON E. FRENCH, a citizen of the United States, residing at Medina, in the county of Medina and State of Ohio, have invented and produced a new and original Design for a Bottle or Similar Article; and I do hereby declare the following to be a full, clear, and exact description of the same, reference being had to the accompanying drawings, forming a part thereof.

This invention relates to a new and original design for a bottle or similar article.

Figure 1 is a perspective view, and Fig. 2 a side elevation.

As shown in the accompanying drawings, the design comprises a substantially-circular body A, of the general shape of a tree-stump, the vertical circumferential wall of which is configured or designed to represent the bark or outside of a stump or portion of a maple tree. At the upper end or top the body from opposite sides inclines upward, as at B, to a substantially-horizontal diametrical ridge or apex, along which is a vertical fin or rib, (indicated at C.) The inclined top portions B have the appearance of the upper portion of a stump which has been cut or hewn by an ax, and the fin has the appearance of the fin which is left on a stump when

a tree is felled with an ax. Projecting upward centrally from the top and at substantially the center of the said fin C is a neck D, shown as circular and in cross-section and having at the upper end thereof spiral ribs or grooves, (indicated at P.) At one side of the body is a flat slab or surface F, the plane of which is parallel to the plane of the fin C. The upper and lower ends of this slab are respectively upwardly and downwardly inclined to meet the circumferential wall of the bottle, as indicated at G and G'.

The essential features of the design are the body having the two inclined upper or top portions B, terminating at a central vertical fin C, and the slab or flat portion F, in a plane substantially parallel to that of the fin C.

Having thus described my design, what I claim as new, and desire to secure by Letters Patent, is—

The design for a bottle or similar article, substantially as shown and described.

In testimony whereof I affix my signature in presence of two witnesses.

RICHMON E. FRENCH.
